UNITED STATES PATENT OFFICE

JAMES L. LARKIN, OF LYNN, MASSACHUSETTS, ASSIGNOR TO FORBES LITHOGRAPH MANUFACTURING COMPANY, OF BOSTON, MASSACHUSETTS, A CORPORATION OF MASSACHUSETTS

DISPLAY STAND

Application filed November 13, 1930. Serial No. 495,357.

This invention relates to display stands and the object is to provide a novel construction of such a stand particularly adapted to support a package of goods for display on a dealer's counter, such, for example, as a carton of candies. The stand may be folded up from a blank formed from a flat sheet or sheets of material such as cardboard. In the preferred embodiment of the invention herein shown, the carton of goods so supported constitutes a dispensing package.

My invention will be well understood by reference to the following description taken in connection with the accompanying drawings, wherein:—

Fig. 1 is a perspective of the device in use;

Fig. 2 is a similar view showing the package of goods removed;

Fig. 3 is a plan view of the blank; and

Fig. 4 is a fragmentary central section through that part of the device which in erected position lies at the front.

In the example of my invention shown in the drawings by way of illustration, the display stand is made from a single piece of cardboard or the like, as shown in Fig. 3, and embodies a suitable panel 5 adapted to be supported in display position, which herein is an upright slanting position. Herein the panel 5 is supported by the rearwardly foldable wings 7 which may be locked in position by the tongue 9 having the slots 11 which embrace the edges of the wings when

they are folded back. The construction of the parts 5, 7 and 9 is substantially like the device of the patent to Wilson 773,177, October 25, 1904, well known in the art, and does not need extensive description herein.

I prefer, however, to provide the bases of the wings 7 with the foldable flanges 13 and their sides with the similar flanges 15, and when the parts are erected the flanges 13 may fold outwardly to provide a relatively broad support, as shown in Figs. 1 and 2, while the flanges 15 may be turned in one direction or the other to stiffen the structure.

From one end of the panel 9 there is provided an extension connected to the panel by the fold line 17, which extension in the

embodiment of the invention shown comprises the parts 19, 21, 23 and 25 joined by the fold lines 27, 29 and 31. The extension is adapted to carry suitable means to aid in supporting a carton in front of the panel 5 and in display position, and I have herein shown as connected to the extension by the fold line 33 a frame-like member 35. The material within the frame provides the rearwardly bendable flanges 37. Referring now to Figs. 1 and 2, when the easel comprising the parts 5 and 7 is erected, the extension may be folded over on itself to bring the frame 35 in front of the panel 5 and the flanges 37 folded rearwardly are adapted to fit about the sides of the easel. A receptacle is thus formed of which the panel 5 is the bottom and in which may be placed the carton 39 containing the packages 41 of goods to be sold, as shown in Fig. 1.

The flanges 37 may be provided with notches 43, one wall of the notches bearing, as shown in Figs. 1 and 2, on top of the extremities of the rearwardly folded tongue 9 to aid in maintaining the latter in position. Preferably also the lower corners of these flanges are bevelled off, as shown at 45, so that they may rest upon the outturned flanges 13.

The extension comprising the parts 19, 21, 23 and 25 in the form shown provides a prismatic structure, herein triangular, the front and rear walls being defined by the parts 21 and 23 and the apex by the fold line 29 between them (see Fig. 4), spaced from the front of the frame member 35 and defining a trough as illustrated. Into this trough the articles 41, especially when they are of cylindrical form as in the case of packages of disc-like candies, may gravitate in the manner shown in Fig. 1. A purchaser may conveniently take one of the packages from this trough and its place will be taken by another gravitating down from the carton 39.

Suitable means may be provided to maintain the extension in its folded-up position and I have herein illustrated suitable means of the tongue and slot type. As best shown by Figs. 3 and 4, a tongue 47 may be cut from the central portion of the part 19, and when the parts are folded up, it may be inserted

through the slot 49 cut in part 25 adjacent the fold line 33, overlie the part 25 and be terminally inserted through slit 51 with its end protruding into the interior of the hollow prismatic structure.

5 Referring to Figs. 1 and 2, I have there shown the top edge of the frame-like member 35 as cut to form bendable tongues 53. I have herein shown the carton 39 as provided at one end with a display card 55 and the 10 tongues 53 may be engaged over this display card in the manner shown in Fig. 1 to hold it in display position.

I am aware that the invention may be embodied in other specific forms without departing from the spirit or essential attributes thereof, and I therefore desire the present embodiment to be considered in all respects as illustrative and not restrictive; reference being had to the appended claims rather than 20 to the foregoing description to indicate the scope of the invention.

I claim:

1. A knock-down display stand of sheet material comprising a folding easel presenting when erected a front face extending in display position, an extension from an end thereof having a plurality of fold lines and terminating in a frame having foldable flanges, said extension adapted to be folded up to provide a prismatic structure at one end of the easel and to dispose said frame before said face, said flanges then fitting about the easel to provide a receptacle.

2. A knock-down display stand of sheet material comprising a folding easel presenting when erected a front face extending in display position, an extension from an end thereof having a plurality of fold lines and terminating in a frame having foldable flanges, said extension adapted to be folded up to provide a prismatic structure at one end of the easel and to dispose said frame before said face, said flanges then fitting about the easel to provide a receptacle, the parts having tongue and slot means to assist in maintaining said structure in folded form.

3. A knock-down display stand of sheet material comprising a folding easel presenting when erected a display face extending in display position, an extension from the lower end thereof having a plurality of fold lines and terminating in a frame having foldable flanges, said extension adapted to be folded up to provide a trough-like structure at the base of the easel and to dispose said frame before said face, said flanges then fitting about the easel to provide a receptacle.

4. A display stand comprising a stand 60 proper having an inclined face extending in display position and a frame-like member having interior flanges to fit about said stand to provide a receptacle of which said face forms the bottom.

5. A knock-down display stand comprising

ing a folding easel of sheet material presenting when erected a front face extending in display position, a frame of sheet material having interior flanges foldable rearwardly to fit over the easel to provide a receptacle of which said face forms the bottom.

6. A knock-down display stand of sheet material comprising a folding easel presenting when erected a front face extending in display position, a foldable extension from an end of said face terminating in a frame-like member adapted to be folded over in front of said face, said member having interior flanges foldable rearwardly to fit over the easel to provide a receptacle of which said face forms the bottom.

7. A display stand comprising a folding easel of the type having a front plate, a standard and a locking tongue having a slit embracing the standard and a part having flanges fitting about said front plate, a flange having an edge overlying the engaged locking tongue.

8. A display stand comprising a panel having associated therewith foldable supporting means for supporting it in display position, said panel having an extension from one end thereof terminating in a collapsible structure for supporting a carton of articles, said structure adapted to lie in front of said panel when the extension is doubled over, the extension comprising a plurality of fold lines to define when so doubled over a trough into which articles from the carton may gravitate.

In testimony whereof, I have signed my name to this specification.

JAMES L. LARKIN.
